DIRECT-CURRENT ENERGIZED CONTACTOR

Ralph B. Immel and Reese T. Kintzing, Wilkinsburg, Pa., assignors to Westinghouse Electric Corporation, East Pittsburgh, Pa., a corporation of Pennsylvania

Application July 20, 1943, Serial No. 495,468

11 Claims. (Cl. 175—372)

This invention relates to direct-current energized contactors, such as relays, switches and the like devices, in which a time-delaying or time-limiting action is desired, and is related to the disclosure in the copending application Serial No. 495,467, filed July 20, 1943, by R. B. Immel, on "Adjustable time-limit devices."

It is an object of our invention to provide an electromagnetic time-limit device which affords an adjustment and change in time limit with considerably greater ease than afforded by the known devices of this type.

More specifically, in this aspect, the invention aims at providing a type of electromagnetic contactor whose manufacture and assembly can be substantially completed regardless of the particular time limit to be obtained and can subsequently be adjusted to the specific time value without disassembly or reconstruction of the magnetic core structure and without separating the contactor body from its supporting frame or permanent circuit connections.

Another object in line with the foregoing is to permit a ready adjustment or change of the time limit by the user of the device, i. e. outside the factory or after the device has been installed in its ultimate place of operation.

While the invention involves using a selective plurality of short-circuited winding elements, it is also among its objects to render the time-limit adjustment more accurate and definitely predetermined than heretofore obtainable. In particular, a definite dependence of the time limit on the selected windings regardless of their specific location along the core portion surrounded by them, is intended.

Still another object, in conjunction with any of those aforementioned, is to facilitate the adjustment of the time limit to such an extent that the adjustment can be carried out without the use of special tools or even without requiring any tools at all.

Lastly, also in conjunction with the foregoing, the invention aims at providing easily manipulated means for fastening the short-circuited winding element in the proper place or removing them therefrom.

In order to achieve these objects, and in accordance with our invention, the magnetizing windings of a time-limit device are arranged so that they surround appertaining magnet core with sufficient play to form an interstice around and along the core, and a removable container or holder is placed into this interstice and provided with a selective plurality of short-circuited

winding elements, each surrounding the magnet core within the magnetizing coil when the container or holder is in its proper place. The time limit of such a device depends on the total resistance, cross section, or number of the inserted elements and is independent of their individual position along the core. An adjustment or change of the time limit can be effected with ease by virtue of the fact that the winding elements are held together by this container or holder and hence can be inserted or removed as a unit.

According to another feature of the invention, the above-mentioned container is provided with means, such as a spring clip, which serve as a handle when removing or inserting the container into the magnet coil and as a fastening device for maintaining the container in place after its insertion.

The foregoing objects and features will be apparent from the following description of the embodiment shown in the drawings.

Figure 1 is a top view of a timing relay according to the invention;

Figure 2 is a part-sectional side elevation;

Figure 3 a front elevation of the same relay; Figs. 4 and 5 show separately the short-circuiting winding assembly of the relay by a part-sectional side view and front view, respectively; and

Fig. 6 is a sectional view of part of another embodiment of the invention.

Referring to Figs. 1, 2 and 3, numeral 1 denotes a magnetizable supporting structure consisting, for instance, of an angular piece of iron. An elongated cylindrical magnet core 2 is mounted on the support 1 and carries at one end a shim disc 3 and a pole piece 4, both attached to the core 2 by means of a riveted projection 5 formed by the core 2. The shim disc consists of a material of high magnetic reluctance, for instance brass. The diameters of the shim 3 and of the pole piece 4 are equal to that of the core member 2 so that the entire core assembly has a straight cylindrical shape over the entire longitudinal extent of the assembly.

A magnetic armature 6 has its upper edge placed against the support 1 and is held in position by means of an abutment plate 7 which is firmly attached to the structure 1. The upper edge of the armature 6 contacting the structure 1 is cut in an acute angle in order to permit the armature 6 rotational movements about the fulcrum formed by the armature edge. A bracket member 8 is firmly secured to the armature 6,

the lower end of this bracket, in the illustrated position, rests against a stationary abutment formed by a metal piece 8 which is mounted on the supporting structure 1. This abutment piece limits the motion of the armature 6 in the direction away from the magnet core 2 and, as illustrated, may contain a screw for adjusting the inactive position of the armature.

A bolt 26 has its lower end journalled to the bracket member 8 and carries a helical spring 18 whose lower end rests against a nut 27 engaging the bolt 26, while the upper end of the spring 18 abuts against the bracket member 8. The bolt 26 carries a cross bar 11 which bridges a recess formed by the abutment plate 7. The two ends of the cross bar are bent away at right angles and form lugs 12 which engage corresponding openings 13 of the abutment plate 7.

When the relay is in assembled condition as represented by Figs. 1, 2 and 3, the spring 18 is under compression and hence pulls the cross bar 11 against the abutment plate 7 thereby securing the lugs 12 in their engagement with the openings 13 while holding the armature 6 and the bracket 8 in the position shown in Fig. 2, in which the bracket member 8 rests against the abutment member 8. In this condition, the compressed spring 18 biases the armature 6 away from the core 2.

A contact member 14 carrying two movable contacts is attached to the armature assembly and cooperates with two stationary contacts 15 and 16 which are firmly connected with the supporting structure 1 in electric contact with terminals 17 and 18, respectively. In the illustrated position, the contact member 14 is moved away from the stationary contacts 15 and 16. When the armature is attracted by the magnet core 2 against the force of spring 18, the contact member 14 engages the stationary contacts to form an electric connection between terminals 17 and 18 through contact members 15, 14 and 16.

As apparent from Figs. 1, 2 and 3, the armature 6 and all other parts assembled therewith can be readily removed from the supporting structure 1 and its appertaining parts by pulling the cross bar 11 out of engagement with the openings 13 of the abutment plate 7 and then moving the cross bar and the armature 6 away from the magnet core 2. In the opposite manner, the assembly can be inserted into the relay. When the armature assembly is removed, the front surface of the core structure is readily accessible.

A magnetizing direct-current coil 19 is mounted on a supporting structure 1 so as to surround the core member 2 with sufficient play to form a cylindric interstice between the core and coil. Two bolts 20 and 21 serve to fasten the structure 1 to a suitable base.

As apparent from Figs. 2, 4 and 5, a tubular container 30 is placed in the interstice between the magnet core and the magnetizing winding. The container has an annular end wall 31 provided with a circumferential groove 32 which is engaged by a depressed portion of the cylindrical wall 30 and thus fastened to the cylindrical wall. Another front ring 31' having a circumferential groove 32' is similarly attached to the other end of the cylinder wall 30. The cylinder wall 30 has a cutout portion at 33 which extends over at least 180° of the periphery in order to permit the insertion and removal of a plurality of ring-shaped short-circuiting winding elements 22. In the illustrated embodiment, four such rings 22 of equal dimensions are provided to fill the entire

axial length of the tubular container. The axial width of the opening 33 is slightly larger than that of the rings 22.

The tubular container 30 and its appertaining parts 31 and 31' as well as the rings 22 consist of an electrically good conductive material such as copper, although other conductive metals or alloys, such as iron or brass, may also be employed. The container and the rings placed therein form a short-circuiting current path around the magnet core 2 which extends entirely within the magnetizing winding 19. The total electric resistance of this current depends on the number of rings 22 placed into the container and hence can be adjusted by selecting a corresponding number of rings 22. The container 30 with its end portions 31 and 31' is preferably so dimensioned that its total electric resistance is substantially equal to that of one winding element 22. Consequently, the illustrated embodiment, requiring four rings 22 to completely fill the container 30, permits six different adjustments of the time constant of the relay. The minimum time constant is obtained when the relay is used without container and rings. A slight degree of retardation is adjusted by placing the container 30 without rings into the magnetizing coil. A greater delay results if the container is provided with a single ring 22, and so forth, the maximum time being obtained when four rings 22 are placed into the container. In this manner, in the embodiment constructed in accordance with Figs. 1 through 5, a range of time delays between approximately $\frac{1}{10}$ of a second up to $1\frac{1}{4}$ or almost up to 2 seconds could be obtained.

While the just-mentioned adjustment is limited to a number of definite retardation steps, the relay permits also a time adjustment to intermediate values by changing the force of spring 18 with the aid of adjusting nut 27. In this manner, any desired time limit between the available minimum and maximum can be adjusted.

Due to the fact that all short-circuiting winding elements when properly inserted into the magnetizing coil 19 lie within the axial length of the magnet core which is surrounded by the magnetizing coil, the location of the individual elements 22 within the container 30 has no noticeable effect on the adjusted time limit. For instance, if only one element 22 is inserted into the tubular container, the time limit remains the same whether the element lies next to the supporting structure 1 or close to the armature 6 or in some intermediate position.

As shown in Figs. 4 and 5, a spring clip 34 is hinged to the front portion 33 of the tubular container at 35 and 36. The clip has a center portion 37 which is bent towards the magnet coil and, in the illustrated position of the clip, engages a circumferential groove 32 of the core structure. This engagement secures the tubular container and the winding elements housed therein in proper position relative to the coil and the core. By forcing the clip portion 37 out of the groove 32, the clip is disengaged and can then be used as a convenient handle for pulling the container out of the magnetizing coil when a change in time limit adjustment is necessary.

The modification illustrated in Fig. 6 refers to a timing relay which is designed in accordance with Figs. 1, 2 and 3, with the exception that the short-circuiting winding elements and their holder are constructed in a manner different from the one represented by the preceding figures. According to Fig. 6, the holder 38' for the

ring-shaped winding elements 22' consists of a tube which is removably placed over the magnet core 2 within the interstice between the core and the magnetizing coil 19. The tube 30' has an exterior thread and the elements 22' form screw nuts and engage the thread. The elements 22' are preferably provided with bores 40 in order to facilitate threading them onto the tube 30' and for permitting an easy removal of the entire tube assembly from the magnetizing coil 19 by placing a wire through one or several bores 40 of the outermost element 22'. The minimum delay limit is obtained when only the tube 30' is placed into the interstice and the maximum delay when the entire length of the tube 30' is covered with winding elements 22'.

Since, as shown by the above-described examples, our invention is capable of modification without departing from its spirit and scope, we wish this disclosure to be considered as illustrative and not in a limiting sense.

We claim as our invention:

1. In an electromagnetic time limit device, the combination of a magnetic core member, a magnetizing coil surrounding said member and forming a peripheral interstice therewith, a container removably arranged in said interstice and surrounding said member within said coil, and a plurality of short-circuiting winding elements removably arranged in said container to permit changing the time limit of the device by a corresponding selection of said elements.

2. In an electromagnetic time limit device, the combination of a magnetic structure having a base member, an elongated core attached at one end to said base member and an armature linked to said base member opposite the other end of said core, a magnetizing coil disposed around said core and spaced therefrom to form a peripheral interstice, a container adapted to surround said core within said interstice and being removable from said core member towards said other end, and a plurality of annular elements of electrically conductive material removably arranged in said container to permit adjusting the time limit of the device by a corresponding selection of said elements.

3. In an electromagnetic time limit device, the combination of a magnetic core member, a magnetizing coil surrounding said member and forming a peripheral interstice therewith, a container removably disposed in said interstice around said member and consisting of electrically conductive material so as to form a short-circuiting winding element, and a plurality of electrically conductive annular elements removably arranged in said container to permit changing the time limit of the device by a corresponding selection of said elements.

4. In an electromagnetic time limit device, the combination of a magnetic core member, a magnetizing coil surrounding said member and forming a peripheral interstice therewith, a container removably arranged in said interstice and surrounding said member within said coil, a plurality of short-circuiting winding elements removably arranged in said container to permit changing the time limit of the device by a corresponding selection of said elements, and an attachment hinged to said container for fastening it in proper position relative to said member and forming a handle for removing said container and elements from said interstice.

5. In an electromagnetic time limit device, the combination of a magnetic structure having a

base member, an elongated core attached at one end to said base member and an armature linked to said base member opposite the other end of said core, said core having a recess at its periphery near said other end, a magnetizing coil disposed around said core and spaced therefrom to form a peripheral interstice, a container disposed to surround said core within said interstice and being removable from said core member towards said other end, and a plurality of annular elements of electrically conductive material removably arranged in said container to permit adjusting the time limit of the device by a corresponding selection of said elements, and a clip linked to said container so as to form a handle when removing said container and disposed to engage said recess for securing said container in proper position relative to said core when inserted into said interstice.

20 6. In an electromagnetic time limit device, the combination of a magnetic core member, a magnetizing coil surrounding said member and forming a peripheral interstice therewith, a container removably arranged in said interstice and surrounding said member within said coil, a plurality of electrically conductive rings matching the peripheral dimensions of said container, said container having an opening at its peripheral surface for inserting said rings to permit changing the time limit of the device by a corresponding selection of said elements.

25 7. In an electromagnetic time limit device, the combination of a magnetic core member, a magnetizing coil surrounding said member and forming a peripheral interstice therewith, a container removably arranged in said interstice and surrounding said member within said coil, a plurality of rings dimensioned to be stacked over one another within said container, said container and 30 said rings consisting of electrically conductive material and forming short-circuited winding elements of approximately equal delaying effect on the operation of the device so as to permit adjusting the total time limit by a selection in 35 number of said elements.

40 8. In an electromagnetic time limit device, the combination of a magnetic structure having a core member, a magnetizing coil surrounding said member so as to form a peripheral interstice therewith, said coil being firmly secured to said structure so as to be supported independently of said core member, a plurality of short-circuited winding elements disposed to be removably inserted into said interstice for surrounding 45 said member within said coil, and holding means engaging said elements for removing them together in order to vary the time limit of the device by a corresponding selection of said elements.

50 9. In an electromagnetic time limit device, the combination of a magnetic core member, a magnetizing coil surrounding said member so as to form a peripheral interstice therewith, a plurality of electrically conductive rings disposed to be 55 removably inserted into said interstice for surrounding said member within said coil, and a holding device for engaging said rings to permit removing them together from said interstice, said holding device having means outside said interstice for fastening said holding device and rings to said member, said means forming also a handle for facilitating the removal of said holding device and rings.

60 10. In combination with a magnetic core of a timing relay, a short circuited winding for in-

creasing the time limit of the relay, said winding having a cylindric container of electrically conductive material removably surrounding said core, and a plurality of electrically conductive annular elements movably arranged in said container for permitting an adjustment of the relay time constant by a corresponding insertion and removal respectively of said elements from said container.

11. In combination with a magnetic core of a timing relay, a short circuited winding for increasing the time limit of the relay, said winding having a container of electrically conductive material removably surrounding said core, and a

5 plurality of electrically conductive annular elements movably arranged in said container for permitting an adjustment of the relay time constant by a corresponding insertion and removal respectively of said elements from said container, having annular end walls and an opening in its peripheral wall, and electrically conductive rings matching the peripheral dimensions of said container and the longitudinal width of said opening to be placed into said container through said opening for adjusting the time limit by selecting the number of the inserted rings.
